UNITED STATES PATENT OFFICE

145,370

DESIGN FOR A SWEATER

Berté A. Wiechmann, Portland, Oreg., assignor to Jantzen Knitting Mills, a corporation of Oregon

Application March 16, 1946, Serial No. 127,593

Term of patent 3½ years

(Cl. D3—4)

To all whom it may concern:

Be it known that I, Berté A. Wiechmann, a citizen of the United States, residing at Portland, in the county of Multnomah, State of Oregon, have invented a new, original, and ornamental Design for a Sweater, of which the following is a specification, reference being had to the accompanying drawing, forming a part thereof.

In the drawing, the single figure is a view of the front side of the sweater showing my new design, the design on the rear side of the sweater being the same as on the front.

I claim:

The ornamental design for a sweater, substantially as shown and described.

BERTÉ A. WIECHMANN.

Certificate of Correction

Design No. 145,370.

August 6, 1946.

BERTÉ A. WIECHMANN

It is hereby certified that error appears in the printed specification of the above numbered patent requiring correction as follows: Second column, lines 3 and 4, strike out the comma and words "the design on the rear side of the sweater being the same as on the front"; and that the said Letters Patent should be read with this correction therein that the same may conform to the record of the case in the Patent Office.

Signed and sealed this 10th day of December, A. D. 1946.
